UNITED STATES PATENT OFFICE.

WILLIAM HAMMOND McOMBER, OF EAST CHICAGO, INDIANA.

AWNING.

1,342,452.

Specification of Letters Patent.

Patented June 8, 1920.

Application filed July 18, 1919. Serial No. 311,729.

To all whom it may concern:

Be it known that I, WILLIAM H. McOMBER, a citizen of the United States, and a resident of East Chicago, in the county of 5 Lake and State of Indiana, have invented certain new and useful Improvements in Awnings, of which the following is a specification.

10 My invention is an improvement in awnings, and has for its object to provide a device of the character specified, adapted for internal use at windows or other openings, for supplying a continuous current of cool air to a sleeper in the bed adjacent to 15 the window, and for constraining the air to flow in at the lower part of the casement over the face of the sleeper and out above the upper casing.

In the drawings:—

20 Figure 1 is a side view of the improved awning in use, with parts broken away.

Fig. 2 is a front view of the awning detached.

25 In the present embodiment of the invention, the awning is shown in connection with a window casement 1 having the usual upper and lower sashes 2 and 3 mounted to slide in the casement. The awning comprises a suitable frame 4 which is hinged 30 to the casement as indicated at 5 at opposite sides thereof, and a curtain or covering 6 connected with the frame, and with the casement at its top as indicated at 7.

35 This covering depends below the frame far enough to touch the mattress 8 of the bed which is arranged at the casement, with the head of the bed just below the casement sill. When not in use, the frame may be folded upward, to leave the lower portion 40 of the window clear, and the covering may be of any suitable or desired material proper for the purpose.

45 In order to provide for a proper circulation of air, a deflecting curtain consisting of portions 9 and 10 is arranged within the awning, the edges of the said portions 9 and 10 being secured to the side walls of the covering, as for instance, by stitching or in any other suitable or desired manner.

50 In use, the device is arranged as shown in Fig. 1, with the deflector 9—10 so arranged that when the upper sash is lowered a few inches, the opening thereof will regis-

ter with the space between the portion 9 of the deflector and the top of the covering 55 for the awning. The portion 10 of the deflector is spaced far enough above the bottom edge of the covering 6, so that when the lower sash is raised from four to six inches, 60 the air from the exterior may pass below the said portion 10.

The person occupying the bed lies with his or her head beneath the awning, and it will be evident that the fresh air from the outside will flow in below the raised lower 65 sash and will pass upward and out through the passage 11 between the portion 9 of the deflector and the inclined portion of the awning. Thus there will be at all times a free and continuous circulation of air from 70 the outside to the sleeper.

The aspired air will pass outward from the passage 11, and at the top of the window. With this arrangement, the occupant of the bed may retire and arise in a warm 75 room, which may be comfortably warm, since the head and shoulders or even the head only, need be exposed, the interior of the room remaining at a considerable temperature. The covering and the deflector 80 may be made of any suitable or desired material.

I claim:—

1. A device of the character specified, for use in connection with windows, comprising 85 an awning frame connected with the casement and supporting a covering connected to the casement at the top and sides thereof and open at the bottom, and adapted to receive the head end of the bed beneath the 90 said open bottom, and means within the covering for causing the circulation of air from the lower part of the window and out at the top of the window, said means comprising a deflector of flexible material connected 95 to the side walls of the awning covering, and consisting of a portion approximately horizontal for deflecting the air entering at the lower part of the window away from the window, and a portion inclined above said 100 first named portion and in substantially parallel spaced relation to the awning covering top for conducting air to the top of the window.

2. A device of the character specified, comprising an awning having a transversely ex-

tending partition within the same consisting of a portion arranged in substantially parallel spaced relation to the inclined top of the awning, and a portion extending at an acute angle with respect to the said first named portion, and adapted to abut the surface to which the awning is connected.

3. A device of the character specified, comprising an awning adapted to be connected to the inside of a window to provide a tent for the head of a bed, and means for constraining the air to flow near that portion of the awning remote from the window.

WILLIAM HAMMOND MCOMBER.
